UNITED STATES PATENT OFFICE.

URASABURO TOMITA, OF NEW YORK, N. Y., ASSIGNOR TO MORIMURA BROS. INC., OF NEW YORK, N. Y., A CORPORATION OF JAPAN.

DESIGN FOR A PLATE OR SIMILAR ARTICLE.

Application filed September 2, 1926. Serial No. 18,934. Term of patent 7 years.

To all whom it may concern:

Be it known that I, URASABURO TOMITA, a subject of the Emperor of Japan, residing in the city of New York, county of Bronx, and State of New York, have invented a new, original, and ornamental Design for pieces, to wit, the dinner plate of a dinner set, showing my new design, it being understood that the ornamentation shown in the drawing is repeated around the circle of the plate.

Plate or similar article, of which the following is a specification, reference being had to the accompanying drawing, forming part hereof.

I claim:

The ornamental design for a plate or similar article, as shown.

URASABURO TOMITA.
